UNITED STATES PATENT OFFICE.

JOEL T. RICE, OF NEW YORK, N. Y.

AIRCRAFT PROPELLING AND CONTROLLING MEANS.

Application filed March 1, 1928. Serial No. 258,262.

The invention relates to aircraft propelling and controlling means of the general type in which a propeller whose axis normally extends longitudinally of the craft, is movable about a pivotal axis to vary the direction in which the force of said propeller is exerted, and the present disclosure of the invention is directed to means of the above defined type in which the propeller is directly carried by a motor, and both motor and propeller are turnable about the pivotal axis.

One object of the invention is to provide new and improved means for mounting a motor-supporting base upon a fixed base in such manner as to readily permit turning of said motor-supporting base about the desired pivotal axis and to effectively hold the two bases against other relative movements.

A further object is to make unique provision whereby control means for the motor will not be disturbed in any adjustment by turning of the movable base about its pivotal axis.

A still further object is to provide a novel and advantageous relation of pivotally mounted propellers and control means for turning them about their pivotal axes.

A still further aim is to provide propelling and controlling means for an air or seaplane, of such nature as to extricate the plane from side slippage, and from nose or tail dives or spins.

With the foregoing in view, the invention resides in the novel subject matter hereinafter described and claimed, description being accomplished by reference to the accompanying drawings.

Fig. 1 is a side elevation of a dirigible embodying my invention.

Fig. 2 is a top plan view of the parts shown in Fig. 1, partly broken away.

Fig. 3 is an enlarged horizontal sectional view substantially on line 3-3 of Fig. 1.

Fig. 4 is a vertical longitudinal section substantially on line 4-4 of Fig. 3.

Fig. 5 is a side elevation partly broken away and in section showing an airplane embodying the invention.

Fig. 6 may be considered as a top plan view with parts broken away and in section, show-

ing the construction and relation of parts disclosed in Fig. 5, with the exception that the two lateral motors and associated parts are disposed more closely to the front of the fuselage than in Fig. 5.

Fig. 7 is a side elevation of a portion of a dirigible airship provided with an underslung gondola at its front end illustrating my invention for propelling and controlling said airship, said invention being carried by said gondola.

In Figs. 1 and 2, the numeral 7 designates the main body of a dirigible, and 8 and 8' denote front and rear assemblies of parts which may either in themselves constitute complete gondolas, or may form portions thereof. As the construction of both assemblages 8-8', is the same, only one will be described, and reference may be had more particularly to Figs. 3 and 4, showing the various features of construction on a large scale, whereas in Figs. 1 and 2, certain parts are of necessity shown rather diagrammatically.

The numeral 9 denotes a fixed horizontal base which is suspended by appropriate hangars 10 and may well be provided with a pilot's seat 11 and with concentric control wheels 12-12' secured to shafts 13-13' disposed one within the other and mounted in appropriate bearing means 14.

Disposed at the upper side of the fixed base 9, is a motor-supporting base 15 which is horizontally disposed and is provided with a peripheral edge of circular outline and formed with gear teeth 16. This base 15 is rigidly joined to a motor 17 which directly carries a propeller 18 whose axis is disposed longitudinally of the dirigible. Base 15 is mounted for pivotal movement about a vertical axis, and is held against other movement with respect to the base 9, by the construction described below.

19 denotes a tubular king bolt or pivot which is concentric with the circular peripheral edge of the motor-supporting base 15 and connects the two bases 9-15, anti-friction bearings 20 being preferably associated with this king bolt or pivot, as shown. Portions 21 of controls for the motor 17, pass either through the tubular pivot or king bolt 100

19, or through some other appropriate part disposed at the pivotal axis of the base 15, so that turning of this base and the motor 17 about said pivotal axis, will not effect the 5 controls in any adjustments of the latter and will consequently not increase or decrease the speed of the motor. The controls shown, may be considered as Bowden wires or analogous devices.

10 Spaced apart about the base 15, are a plurality of U-shaped brackets 22 whose arms straddle the peripheral portion of said base 15, and an additional bracket 23, provided with no lower arm, is also employed. The 15 brackets 22 are provided with outwardly projecting attaching portions 24 secured by bolt and slot connections 25—26, to the fixed base 9, and bolts or the like such as 27, are provided to secure the bracket 23 to said fixed base 20 9. The upper and lower arms of the brackets 22, carry anti-friction rollers or other desired bearings 28 which engage the upper and lower sides of the base 15, and similar rollers or the like 29 are carried by the brackets 23, 25 in contact with the upper side of said base 15. Pinions 30 meshing with the gear teeth 16, are mounted between the upper and lower arms of the brackets 22, and another pinion 31 which also meshes with said gear teeth, 30 is mounted on a short vertical shaft 32 rotatably supported partly by the bracket 23 and partly by a bearing on the base 9.

The construction so far described mounts the movable, motor-supporting base 15, upon 35 the fixed base 9, in such a manner that said movable base may readily turn about a vertical axis, yet the two bases are positively held against any movement whatsoever, in any other manner, providing a safe construction 40 which is free from excessive vibrations.

The shaft 32 is provided with a gear 33 meshing with another gear 34 on the shaft 13 and it will be seen that turning of the control wheel 12, will turn said shafts and gears, 45 thus turning the pinions 31 and causing the latter to turn the base 15 to direct the propeller 18 in any desired direction, so that its propulsive force may be exerted in the most advantageous manner, according to the direction 50 to be taken by the ship or according to tendencies of wind to drive the ship from its course.

Rigidly joined to the rear portion of the base 9, are two vertical, fixed bases 9' upon 55 which motor-supporting bases 15', also disposed vertically, are mounted in the same manner as the base 15 is mounted upon the base 9. The bases 15' carry two lateral motors 17' having propellers 18' whose axes normally extend longitudinally of the ship. 60 These lateral motors 17' are provided with suitable side base attachments which are connected to said motor-supporting bases 15' and attain a vertical position of said motors. 65 Pinions 31', corresponding to the pinion 31,

mesh with the peripheral gear teeth of the movable bases 15' and are secured upon a suitably mounted transverse shaft 35. By appropriate gearing 36 this shaft is operatively connected with a longitudinal shaft 37 whose front end is provided with a gear 38 meshing with another gear 39 on the shaft 13'. This shaft is provided with the hand wheel 12' and it will thus be seen that by turning this wheel, the various gears and shafts will be operated to simultaneously turn the bases 15' about their pivotal axes. Thus, the motors 17' and the propellers 18' may be so adjusted as to cause the latter to exert their propulsive forces in any desired direction, that is forwardly, rearwardly, upwardly, downwardly or in intermediate directions. 70 75 80

In Figs. 5 and 6, an airplane 40 is shown to illustrate an advantageous relation of parts thereon, but it is to be understood that such relation is also adaptable to seaplanes. 9^a in these views denotes a fixed horizontal base, 15^a has reference to a supporting base for a motor 17^a provided with a front propeller 18^a, and 22^a may be considered as portions 90 of pivotal mounting means for the base 15^a, similar to or identical with the mounting means disclosed in Figs. 3 and 4. 15^b denotes movable bases carrying two lateral motors 17^b having propellers 18^b spaced laterally from and behind the propeller 18^a. In the same manner as above described, the bases 15^b are pivotally mounted on fixed vertical bases 9^b. By shafting, gearing, etc., the base 15^a is operatively connected with a control 100 wheel 12^a and by similar connections, the bases 15^b are connected with a control wheel 12^b. By turning the wheel 12^a, propeller 18^a is turned horizontally in one direction or the other as occasion may demand and will serve 105 to effectively counteract side slippage of the plane. By turning wheel 12^b, the propellers 18^b may be swung as desired about the pivotal axes of the bases 15^b, to not only assist in effecting vertical movement of the plane, but to expeditiously extricate said plane from either a nose or tail dive or spin. 110

It will be seen from the foregoing that I have herein disclosed certain specific provision for attaining the objects of the invention, 115 but it will be understood that the present disclosure is principally for illustrative purposes and that within the scope of the invention as claimed, numerous variations may be made.

I claim:

1. In an aircraft driving and controlling means, a fixed base, a movable motor-carrying base having a circular edge provided with gear teeth, a central pivot connecting the movable base with the fixed base, a plurality of pinions rotatably mounted on said fixed base and meshing with said gear teeth to assist said pivot in receiving lateral strain, means carried by said fixed base and engag- 125 130 135

- ing the side of the movable base remote therefrom to prevent movement of said movable base bodily away from said fixed base, and means for rotating at least one of said pinions 5 to turn said movable base about its pivotal axis.
2. In an aircraft driving and controlling means, a fixed base, a movable motor-carrying base having a circular edge provided with 10 gear teeth, a plurality of pinions rotatably mounted on said fixed base and meshing with said gear teeth, means carried by said fixed base and engaging the side of the movable base remote therefrom to prevent movement 15 of said movable bodily away from said fixed base, and means for rotating at least one of said pinions to turn said movable base about its pivotal axis.
3. In an aircraft propelling and controlling means, a fixed base, a movable motor-supporting base at one side of said fixed base provided with a gear-toothed peripheral edge of 20 circular outline, U-shaped brackets secured to the fixed base at the periphery of the movable base and having arms straddling the peripheral portion of said movable base, bearing means carried by said arms and engaging opposite sides of said movable base, pinions rotatably mounted between said arms and meshing 25 with the gear teeth of said movable base, and means meshing with said gear teeth for turning said movable base about an axis concentric with said circular edge thereof.
4. In an aircraft propelling and controlling means, a motor-supporting base turnable about a pivotal axis, means for turning said base about said axis, speed control means for the motor on said base, and means receiving and holding a portion of said speed 30 control means at the pivotal axis of said base to prevent disturbing of any adjustment of said portion by turning of said base.
5. In an aircraft propelling and driving means, a fixed base, a motor-supporting base, 35 means mounting said motor-supporting base on said fixed base and embodying a tubular pivot about which said movable base may be turned, means for turning said motor supporting base about said tubular pivot, and speed control means for the motor on said 40 base, embodying a portion passing through said tubular pivot, whereby any adjustment of said portion will remain undisturbed by turning of said base about said pivot.
6. In an aircraft, a front and two lateral 45 motors all having propellers, means mounting said front motor on a vertical pivotal axis, means mounting said lateral motors on horizontal transverse pivotal axes, two axial- 50 ly aligned control wheels disposed in close proximity to each other, means permanently connecting one of said wheels with the mounting means of said front motor for performing the sole duty of turning the latter about its vertical pivotal axis, and means perma-
- nently connecting the other of said wheels with the mounting means of both of the lateral motors for performing the sole duty of simultaneously turning them about their pivotal axes.
7. In an aircraft, a horizontal fixed base, two vertical fixed bases spaced laterally and longitudinally from said horizontal base, a horizontal and two vertical bases pivotally mounted on said fixed bases on a vertical and 70 two horizontal axes respectively, individual motors secured to said pivotally mounted bases respectively, means for turning the horizontal pivoted base independently of the vertical pivoted bases, and means for simultaneously turning said vertical pivoted bases independently of said horizontal pivoted base.
8. In an aircraft, a horizontal fixed base, two vertical fixed bases spaced laterally and 75 longitudinally from said horizontal base, a horizontal and two vertical bases pivotally mounted on said fixed bases on a vertical and two horizontal axes respectively, individual 80 motors secured to said pivotally mounted bases respectively, two control wheels mounted co-axially on said horizontal fixed base, means operatively connecting one of said wheels permanently with said horizontal pivoted base, and means permanently connecting the other of said wheels operatively 85 with said vertical pivoted bases.
9. In an aircraft, a horizontal motor-supporting base, two vertical motor-supporting bases spaced laterally and somewhat to the rear from said horizontal base, the three bases 90 being rigidly mounted, a front vertical-cylinder propeller-equipped motor directly over and having its bottom portion provided with a rigidly attached base connected with said horizontal base to permit turning of the motor about a vertical axis, two lateral vertical-cylinder propeller-equipped motors spaced 95 outwardly from said vertical bases and having their inner sides provided with rigidly attached bases connected with said vertical bases to permit swinging of these motors about horizontal transverse axes, and means whereby said motors may be swung about their pivotal axes.
- In testimony whereof I have hereunto af- 100 fixed my signature.
- JOEL T. RICE.
